2 SHEETS-SHEET 2.

UNITED STATES PATENT OFFICE.

DANIEL R. MURPHY, OF FREDERICKTOWN, PENNSYLVANIA, ASSIGNOR TO H. K. PORTER CO., OF PITTSBURGH, PENNSYLVANIA, A CORPORATION OF PENNSYLVANIA.

COMPRESSED-AIR ENGINE.

1,024,740.

Specification of Letters Patent.

Patented Apr. 30, 1912.

Application filed July 31, 1911. Serial No. 641,526.

To all whom it may concern:

Be it known that I, DANIEL R. MURPHY, a citizen of the United States, and resident of Fredericktown, in the county of Washington and State of Pennsylvania, have invented a new and useful Improvement in Compressed-Air Engines; and I do hereby declare the following to be a full, clear, and exact description thereof.

My invention relates to compressed air engines. Its object is to improve on a construction hitherto employed in certain types of these engines, in which stop valves are provided in the connection between the air reservoir and the initial or high pressure cylinder, the said connection being provided with a reducing valve to reduce the pressure of air entering the valve chest from that of the reservoir pressure to a uniform working point. As hitherto constructed, such engines, as applied to a locomotive, have been provided with a stop valve in front of the reducing valve, which has been controlled in general by an auxiliary air pipe actuating a piston connected to the valve. The purpose of such a stop valve is to prevent the piling up or increase of pressure when the engine is not using air in the connection leading from the reducing valve to the cylinder, and between the throttle valve controlling such connection and the reducing valve itself. This increase of pressure in such connection and the auxiliary reservoir usually included therewith is caused by the leakage of air through the reducing valve, on account of the necessary construction of the same; and results in an excessive pressure of air being admitted to the cylinder when the throttle valve is again opened.

By my invention, I improve on the means hitherto employed for actuating the said stop valve, my invention contemplating its actuation purely by mechanical means operated directly by the throttle lever which controls the throttle valve, so that the stop valve moves in unison with the throttle valve, said means comprising preferably a cam carried by a shaft or rod rotated or oscillated by the throttle lever, and a lever actuated by said cam and actuating the valve stem of the stop valve employed.

My invention also consists in the construction and arrangement of parts as more particularly described and claimed below.

In the accompanying drawings Figure 1 is an end view illustrating my invention as applied to compressed air locomotive engines. Fig. 2 is a side view partly broken away of the same. Fig. 3 is a detail side elevation partly in section illustrating the cam and lever, valve actuating mechanism, and Fig. 4 is a detail vertical section through the stop valve.

In the said drawings, the compressed air locomotive engine illustrated is provided with a suitable frame 1 and driving wheels 2 on the rails 3. The said engine has the main air reservoir 5, the high pressure cylinder 6, and the connection 7, 7' leading from the air reservoir 5 to the cylinder 6. As illustrated, the connection 7, 7' comprises the pipe 7 opening into the auxiliary reservoir 8 and the pipe 7' leading therefrom to the valve chest 9. The elbow 10 leads directly from the reservoir 5 through the casting 11' of the stop valve 11, and through the reducing valve 12 to the pipe 7. The reducing valve 12 shown is of an ordinary adjustable pattern now well understood in the art, being provided with the controlling spring 14 and other parts necessary to its operation which will not be specifically described herein. I have also illustrated an interheater 15 to which the exhaust of the cylinder 6 is connected by a pipe 13, the interheater 15 being connected by the pipe 13 with the valve chest 19 of the low pressure cylinder 20, although the construction and arrangement forms no part of my present invention.

The stop valve 11 has the valve stem 21 which extends through the valve casing 11', being provided preferably with a reduced portion 21' joining the valve head 11 within said valve casing. The effective area, or upper pressure face of the stop valve 11, above the valve seat 22, is thus much greater than the effective area of its opposite pressure face, the difference being substantially equivalent to the horizontal cross section of the portion 21' of the valve stem 21, when the valve is open. There is, therefore, during normal operation of the engine, a force tending to close this valve 11 substantially equal to the product of the pressure per unit area within the reservoir 15 times the cross section of said valve stem portion 21'. When the valve is closed through the with-

drawal of support from the valve stem 21, as described below by the said pressure, however, the pressure within the connection 7, 7' and reducing valve 12 being in general much less than that of the reservoir, and in fact frequently atmospheric only when the engine is dis-used for a time, the difference in pressures is thereby greatly accentuated on the opposite sides of the valve 11. It therefore requires a very great force to raise this valve 11 from this seat 22, although after a material opening is produced, the force necessary is greatly reduced. I therefore provide means, as described below for obtaining a very slow initial opening of the valve 11 and for accelerating its further opening. The valve 11 is raised from such seat 22 by means of the cam 23 which is carried on a rotating or oscillating shaft 24 with which the throttle lever 25 is provided. The said shaft 24 is journaled in the bearings 13 attached to the locomotive frame 1, and the cam 23 is fastened to it preferably by the screw 26 or in any desired fashion. The valve stem 21 is provided preferably with a clevis 27 through which extends the lever 28 pivotally connected thereto by the pin 29 held in position by the head 30 and cotter pin 31. The clevis 27 is preferably screwed onto the valve rod 21 at 27', as shown. The arm 28' of the lever 28 is actuated by the cam 23, being preferably provided with an antifriction roller 32 along which the said cam 23 plays. The opposite end of the lever 28 is fulcrumed by the pin 33 to the adjustable clevis-head 34 attached to the clevis rod 35. The said clevis-head 34 is provided with the adjusting nut 36 and the lock nut 38, which thread on the clevis-rod 35, which is in turn screwed into the lug 39 of the valve casing 11' at 40. The clevis-head 34, and hence the fulcrum-point of the lever 28 is adjustable by means of the said nuts 36 and 38; so that the closure of the valve 11 can be nicely regulated.

The throttle lever 25 is connected through the shaft 24, the arm 41, the connecting rod 42, and the arm 43 to the throttle valve 44, as illustrated in Figs. 1 and 2. The throttle lever 25 is also preferably provided with the usual latch and handle device 45 and segment rack 46.

In operation, when it is desired to start the engine, the throttle lever 25 is moved to open the throttle valve 44. The same movement simultaneously rotates the shaft 24 and cam 23 thereby raising the stop valve 11, and permitting air from the reservoir 5 to pass through the reducing valve 12 and auxiliary reservoir 8 to the cylinder 6. During normal operation the reducing valve 12 continuously reduces the pressure to, say about 250 pounds per square inch in the auxiliary reservoir, the pressure in the main reservoir being much higher, say from 800

to 900 pounds per square inch. If, when the throttle is closed, there were no means for preventing the traveling of the air past the reducing valve 12, the pressure in the auxiliary reservoir 8 and pipe 7, 7', would rapidly rise to that of the main reservoir; and upon the throttle valve 44 being opened, a tremendous gust or blast of air at excess pressure would be admitted to the cylinder 6. By providing the stop valve 11 which is closed at the same time as the throttle valve 44, I prevent the pressure ever rising above the desired maximum amount beyond the reducing valve 12. My invention provides a simple and effective means for accomplishing this object instantaneously upon the closing of the throttle valve. By my invention, also, owing to the shape of the cam 23 employed the initial movement of the valve 11 is slight or very short compared to the travel of the throttle lever in the same time. This enables the throttle lever to be readily operated, and would be impossible by other direct mechanical connection than a cam or its equivalent, as the tremendous reservoir pressure on the valve 11 opposing its opening would create too great resistance to the movement of the throttle lever. As indicated by the shape of the cam 23, the further movement of the valve 11, after an opening for the passage of air has been provided, can be readily accomplished at a higher rate of speed, the cam 23 thus being arranged to impart an accelerating movement to the valve 11.

What I claim is:

1. In compressed air engines, the combination of a compressed air reservoir, an engine cylinder, a connection leading from said reservoir to said cylinder, a reducing valve in said connection, a throttle valve in said connection between said reducing valve and said cylinder, a stop valve in said connection between said reducing valve and said reservoir, and a throttle lever controlling said throttle valve and provided with mechanical means for moving said stop valve when actuated.

2. In compressed air engines, the combination of a compressed air reservoir, an engine cylinder, a connection leading from said reservoir to said cylinder, a reducing valve in said connection, a throttle valve in said connection between said reducing valve and said cylinder, a stop valve in said connection between said reducing valve and said reservoir, a throttle lever actuating said throttle valve, a cam actuated by said throttle lever, and a valve rod connected to said stop valve and actuated by said cam, substantially as described.

3. In compressed air engines, the combination of a compressed air reservoir, an engine cylinder, a connection leading from said reservoir to said cylinder, a reducing valve

- in said connection, a throttle valve in said connection between said reducing valve and said cylinder, a stop valve in said connection between said reducing valve and said reservoir, a throttle lever controlling said throttle valve, a shaft actuated by said lever and provided with a cam, and a lever actuating said stop valve and movable by said cam, substantially as described.
- 10 4. In compressed air engines, the combination of a compressed air reservoir, an engine cylinder, a reducing valve in said connection, a throttle valve in said connection between said reducing valve and said cylinder, a stop valve in said connection between said reducing valve and said reservoir, a throttle lever controlling said throttle valve, a shaft journaled in the engine frame, carrying said throttle lever and provided
- 15 with a cam, and a lever actuated by said cam and connected to said stop valve, substantially as described.
5. In compressed air engines, the combination of a compressed air reservoir, an engine cylinder, a connection leading from said reservoir to said cylinder, a reducing valve in said connection, a throttle valve in said connection between said reducing valve and said cylinder, a stop valve in said connection between said reducing valve and said reservoir, a throttle lever controlling said throttle valve, a shaft journaled in the engine frame, carrying said throttle lever and provided
- 20 with a cam, and a lever actuated by said cam and connected to said stop valve, substantially as described.
- 25 6. In compressed air engines, the combination of a compressed air reservoir, an engine cylinder, a connection leading from said reservoir to said cylinder, a reducing valve in said connection, a valve controlling said connection between said reservoir and said reducing valve, a controlling lever, and mechanism directly connecting the same to
- 30 said last mentioned valve including a cam adapted to progressively actuate said valve, substantially as described.
- 35 7. In compressed air engines, the combination of a compressed air reservoir, an engine cylinder, a connection leading from said reservoir to said cylinder, a stop valve in said connection having opposite pressure faces of different areas, a throttle valve in said connection between said stop valve and said cylinder, a controlling lever, an actuating mechanism connecting said lever to said throttle valve and connecting said lever to said stop valve including a cam adapted to open said stop valve at accelerating speed
- 40 against the pressure of air on its pressure face of greater area, substantially as described.
- 45
- 50
